SMITH O'BLENIS, OF GREENSBURG, PENNSYLVANIA, ASSIGNOR TO HIMSELF AND C. H. STARK, OF THE SAME PLACE.

Letters Patent No. 67,209, dated July 30, 1867.

IMPROVED CAR-COUPING.

The Schedule referred to in these Letters Patent and making part of the same.

TO ALL WHOM IT MAY CONCERN:

Be it known that I, SMITH O'BLENIS, of Greensburg, in the county of Westmoreland, and State of Pennsylvania, have invented a new and useful Improvement in Car-Couplings, of which the following is a full, clear, and exact description, reference being had to the accompanying drawings, which make part of this specification, and in which—

Figure 1 is a vertical longitudinal section through my improved car-coupling.

Figure 2, a view of the hook which holds the coupling-link, detached; and

Figure 3, a diagram showing the operation of the hook.

To carry out my invention I construct a coupling-box or casing A, having a flaring or bell-mouth B, (into which the link C is inserted when two cars are coupled together,) at its outer end, and a bolt, D, at the other, by which the box may be secured to the end of the car. A hook, E, of the peculiar form shown in the drawings, has a slot, e, in its rear end. A bearing-pin, f, passes through this slot and sustains the rear end of the hook, which arrangement allows the link to play back and forth horizontally on its bearing. A spiral spring, g, encircles the hook and bears against the pin f, so that the hook is always thrust forward in the box A as far as the slot will permit it to go. A coiled spring, h, encircles the bearing-pin and serves to keep the hook down upon the bottom of the casing. The hook is provided with a handle, l, which plays in a slot, m, in the casing, which slot serves as a guide for the hook. A bill or catch, i, on the hook, receives and holds the link C. Just back of this hook the link is flared and hollowed out to form a dome-shaped recess, k, which receives, guides, and holds the link in the proper position for the hook when it enters. In fig. 3 the black lines show the normal position of the link, the blue lines its position when pushed in, and the red lines its position when lifted to uncouple the cars.

The operation is as follows: A coupling is placed on each end of the cars, as usual, and the link C inserted into one, as shown in fig. 1. The spring h holds the coupling horizontal by holding down the hook. As the cars approach the link C enters the bell-mouth B and strikes the catch i (the outer face of which inclines backward and downward) with sufficient force to raise the hook and enter the recess k. As soon as the link passes the catch i the spring h throws it down behind the link. The end of the link now abuts against the dome k, the spring g yields and prevents shocks to the coupling until the bumpers abut. As the cars separate the link is held by catch i, and the cars are thus securely coupled. A cord may be connected to the handle l to lift the link to uncouple the car, but it may be done by hand by a person on the platform with ease.

As by my invention the cars are coupled automatically, it is obvious that I dispense with the necessity of a person going between the cars to couple them, which necessity is the source of so many accidents.

What I claim as my invention is—

1. The hook E, constructed, arranged, and operating as described.
2. The combination, substantially as described, with the bell-mouthed casing, of the slotted yielding coupling-hook, having both a horizontal and a vertical movement in its bearing, whereby the hook acts as a bumper, and is also made self-locking.

In testimony whereof I have hereunto subscribed my name.

SMITH O'BLENIS.
